RAZOR SHEATH

Victor B. Hueber, Englewood, N. J., assignor to
Durham Duplex Razor Company, a corporation
of New York

Application June 6, 1932, Serial No. 615,615

4 Claims. (Cl. 30—12)

This invention relates to razors and particularly to protecting sheaths or cases for the blade and blade holding parts of safety razors.

Its object is to provide a simple and inexpensive sheath which can be slipped on and off the blade holding parts so that the razor can be thrown into a traveling bag with other articles and will yet be instantly available for use.

Another object is to provide such a sheath with means for retaining the same on the razor without appreciably adding to cost or interfering with quick removal.

Since razor blade holders are sold at a very low price it is an object of the invention to produce a sheath of this type which adds very little to the cost of the entire unit. Still another object is to take advantage of the construction of certain types of safety razors to retain the sheath thereon. Still another object is to provide a sheath or case which will fit both the type of razor which has a handle at one end of the blade and the type which has a handle projecting at right angles to the blade intermediate to the ends thereof.

With these and other objects not specifically mentioned in view the invention consists in certain constructions and combinations which will be hereinafter fully described and then specifically set forth in the claims hereunto appended.

Referring now to the drawing, which forms a part of this specification and in which like characters of reference indicate the same or like parts, Fig. 1 is a plan view of a safety razor having the improved case; Fig. 2 is an elevation or edge view of the razor and case shown in Fig. 1; Fig. 3 is a plan view showing the application of the invention to another type of razor; Fig. 4 is an end view of the razor and case of Fig. 3; Fig. 5 is a detail plan view of the improved sheath or case; Figs. 6 and 7 are sections on the lines 6—6 and 7—7 respectively of Fig. 5; Fig. 8 is a plan view of the modified form of the improved case; and Figs. 9 and 10 are sectional views on the lines 9—9 and 10—10 respectively of Fig. 8.

In carrying the invention into effect there is provided the combination with a safety razor blade holder and guard one having an aperture for receiving a securing element on the other, of a sheath for said holder and guard provided with a yieldable projection on the inside of said sheath positioned to engage in said aperture to retain the sheath on the holder and guard. In the best constructions the sheath is of resilient material and the yieldable projection consists of a boss

formed from said resilient material. The various means referred to may be varied widely in construction within the scope of the claims, for the particular device selected to illustrate the invention is but one of many possible concrete embodiments of the same. The invention therefore is not to be restricted to the precise details shown and described.

The safety razor shown in Figs. 1 and 2 consists of a handle 11, secured to a guard 12 having lugs 13 engaging in apertures 14 of a holder or clamp 15 to secure the blade 16 to the guard and handle. The sheath or case comprises, in the form shown in Figs. 3 to 7 inclusive, a pair of interfitting shells 17 and 18 having inter-fitting flanges 19 and 20 which are preferably cemented together although they may be otherwise secured. One of these shells is provided on its inner side with a boss 21 the depression resulting being closed by a disk 22 on the outside of the shell. As shown in Fig. 6 the boss is in a raised portion of the shell running lengthwise thereof and on the other shell is a corresponding depressed or inwardly extending portion also running lengthwise of the shell. In order that the same shell may fit razors of the type in which the handle projects at right angles from the mid portion of the holder the portion of the case opposite the boss is slotted at 23 for a little more than half the length of the case to receive the handle.

The case shown in Figs. 6 and 7 is preferably made of resilient sheet material such for instance as celluloid although it could be made of metal or other material. Accordingly the boss 21 will have sufficient resilience and be resiliently carried by the shell 17 so that its inwardly extending portion may drop into the lug receiving aperture 14 of the blade holder thus resiliently retaining the case in place over the razor blade holder while permitting it to be readily slipped off.

In the form shown in Figs. 8, 9 and 10, a tube of sheet material forming the body 25 of the case is provided. This tube is preferably cemented along the longitudinal seam 26 and is of an inside diameter or dimension slightly less than the external dimension of the guard, such that it frictionally engages the teeth of the guard 12 or other extending parts of the blade and holder of the safety razor. This tube is made of resilient sheet material and thus will be retained on the blade by a resilient frictional grip thereon of the slightly distorted tube. This tube may be made in a wide variety of shapes including

rectangular shapes. Its end is closed by means of a cap 27 and is provided with a slot 28 similar to that in the form shown in Figs. 1 to 7 for permitting entry of the perpendicular handle 5 type of holder shown in Fig. 4.

In the preferred embodiment all of the sheaths are made of transparent celluloid for the purpose of better displaying of the razor and because of the resulting pleasing appearance.

16 What is claimed is:

1. The combination with a safety razor blade holder and guard, one having an aperture for receiving a securing element on the other, of a sheath for said holder and guard provided with 15 a yieldable projection on the side of said sheath positioned to engage in said aperture to retain the sheath on the holder and guard.

2. A sheath for razors comprising two interfitting shells of resilient sheet material cemented together along their edges, one of which has 20 an outwardly extending raised portion provided

with an inwardly extending projection for resiliently engaging a razor therein and retaining the sheath on the razor.

3. The combination with a safety razor blade clamp and guard, the clamp having an aperture for receiving a securing element on the guard, of a sheath for said clamp and guard, one side of said sheath having a raised portion provided with a yieldable projection positioned to engage in said aperture to retain the sheath on the clamp and guard.

4. The combination with a safety razor blade clamp and guard, the clamp having a cavity in its outer longitudinal surface, of a sheath of resilient material having an outwardly extending raised portion on one side thereof provided with a resilient inwardly extending boss positioned to resiliently extend into the cavity to retain the sheath on the clamp.

VICTOR B. HUEBER.
